UNITED STATES PATENT OFFICE

MACLYN GUHL, OF FOREST HILLS, NEW YORK, ASSIGNOR TO WILLIAM WILLHEIM CO., INC., OF NEW YORK, N. Y.

DESIGN FOR A TEXTILE FABRIC OR SIMILAR ARTICLE

Application filed January 28, 1933. Serial No. 47,025. Term of patent 3½ years.

To all whom it may concern:

Be it known that I, MACLYN GUHL, a citizen of the United States of America, residing at Sutton Hall, Forest Hills, Long Island, New York, have invented a new, original, and ornamental Design for a Textile Fabric or Similar Article, of which the following is a specification, reference being had to the accompanying drawing, forming a part thereof.

The figure is a plan view of a textile fabric showing the complete width of the fabric to which my new design is applied, except for

the portion between the break lines which is similar to that on either side thereof. The dot and dash lines on the drawing outline substantially the design unit, which unit is repeated in regular succession as indicated by the extensions beyond the unit boundaries.

I claim:

The ornamental design for a textile fabric or similar article as shown and described.

In testimony whereof I have signed this specification.

MACLYN GUHL.
